(57) **CLAIM**

The ornamental design for a telescopic robotic arm, as shown and described.

DESCRIPTION

FIG. 1 is a perspective view of a telescopic robotic arm showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 shows an embodiment in which both ends of the telescopic arm are pulled. The broken lines depict portions of the telescopic robotic arm that form no part of the claimed design.
